CLAIM

The ornamental design for a partitioned container, as shown and described.

DESCRIPTION

FIG. 1 is a perspective view of a partitioned container showing my new design;

FIG. 2 is left side view thereof;

FIG. 3 is a front view thereof;

FIG. 4 is a right side view thereof;

FIG. 5 is a back view thereof;

FIG. 6 is a top view thereof;

FIG. 7 is a bottom view thereof; and,

FIG. 8 is a perspective view of a partition panel, shown separately for completeness of illustration.
